UNITED STATES PATENT OFFICE

2,627,309

AWNINg STRUCTURE

James N. Dugan, Cincinnati, Ohio

Application August 23, 1949, Serial No. 111,955

5 Claims. (Cl. 160—202)

1

The present invention relates to an improved awning structure for windows and other wall openings to be protected from the elements of nature.

An object of the invention is to provide an awning structure which is simple and inexpensive to manufacture and install.

Another object is to provide an improved awning which is highly effective to intercept sunshine and rain while permitting light to pass, and which is easily and quickly adjustable to operative and inoperative positions.

A further object is to provide an awning of the character stated, which can be formed of sheet material which is more rigid and durable than woven fabric, while at the same time retaining the general appearance of a fabric awning.

Another object is to provide an improved adjustable awning which is durable, rigid, and wear resistant, the construction being such as to avoid the occurrence of rattle, vibration, and noises resulting therefrom when the structure is subjected to wind and rain.

Still other objects of the invention are: to make possible the installation of the awning from inside the building; to provide for adjustment without opening the window; to avoid frequent replacements and repairs; to provide ample ventilation; and to avoid darkening the room unnecessarily when the awning is in the operative or lowered position.

The foregoing and other objects are attained by the means described herein and illustrated upon the accompanying drawing, in which:

Fig. 1 is a perspective view of the awning structure of the invention, shown applied to a simplified form of window frame, the details of the frame being omitted from the drawing in the interest of clarity.

Fig. 2 is an enlarged cross-sectional view taken on line 2—2 of Fig. 1, and showing the awning in the operative or lowered position.

Fig. 3 is a side elevational view on a reduced scale, showing a modification of the awning structure.

Fig. 4 is a perspective view showing a modification.

Fig. 5 is a perspective exploded view of the Fig. 4 modification.

It has been common practice heretofore, to fabricate awnings and shades from sheet metal, wherefore no claim is made herein to originality in that broad idea. However, such devices as heretofore constructed were found objectionable for various reasons, and as a consequence they have not enjoyed widespread public acceptance.

2

The structural improvements embodied in the device of the present invention are effective to provide a most satisfactory and practical adjustable awning, free of all the objectionable features which have had a limiting effect upon the widespread sale and usage of metallic awnings.

With reference to the accompanying drawing, the numeral 5 in each instance designates any common form of window frame having stiles 6, a head piece 7, and a sill member 8. It should be understood that window frames are variously constructed, and that the drawing depicts only the essential elements of any ordinary window frame, the details of which are omitted in the interest of clarity of disclosure. Irrespective of the frame details, the nature of the counterweighting mechanism, the trim, the sash guides, etcetera, the awning structure of the present invention is generally applicable.

In Figs. 1 and 2, the awning structure is shown as comprising an upper fixed canopy 9, and a lower movable shade member 10 adapted for vertical shifting movement into and from the interior of the canopy. The canopy 9 may be of substantially the same size and shape as the shade member, or as disclosed by Fig. 3 it might be reduced as to the extent of projection outwardly from the window frame. In either case, the inclined forward panels 12 and 13 are disposed substantially at a common angle to the window frame, in order that the movable member might be elevated as far as possible into the canopy.

If desired, the parts 9 and 10 may be provided with any suitable form of drop or decorative skirt 14, preferably of metal or other durable sheet material, which may lend rigidity and attractiveness of appearance to the awning structure as a whole. The skirts or drops may be fixed to the forward panels, and to the side panels 15, utilizing any conventional type of crimp joint or weld; or if desired, the skirts or drops may be formed integrally with the front and side panels.

At the upper edge, the canopy panel 12 may be turned rearwardly at an angle to provide a flange 16 extending preferably along the full length of the panel. This flange may be perforated at intervals to receive lag screws or other fasteners 17 securing the flange to the under face of head piece 7. The canopy may be further supported upon the window frame by means of a series of lag screws or the like 18 passing through flanges 19 which extend inwardly from each of the side panels 15. Flanges 19 preferably are integral parts of the side panels, and extend at right angles therefrom.

Near the upper end of each flange 19 is pro-

vided a bracket 20, which is adapted to support the upper end 21 of a vertical guide member or rod 22 upon which the movable shade 10 may shift. The bracket 20 may be formed from the metal of the flange 19, if desired. To accommodate the guide or rod end 21, the bracket may be pierced or otherwise formed to embrace the rod end. The lower end of the rod may be bent, flattened, and pierced to accommodate a suitable fastener, such as a lag screw 23, whereby the rod is fixed to a stile of the window frame at that point. Two such guide rods are provided, one at each side of the window frame, to guide the opposite sides of the movable shade member 10.

To ensure smooth vertical shifting movement of the shade member 10 into and from the canopy, the shade member is furnished with eyes or sleeves 24 attached thereto in any suitable manner, and in which the guide rods 22 are slidably received. To adjust the shade member to different elevations along the rods, a suitable actuating means may be employed. By preference, though not of necessity, the actuating means is adapted for manipulation from the rear of the window frame, that is, without necessarily opening the window and reaching through the opening. One desirable type of actuator is in the form of a cord or cable 25 having one end attached to the movable shade member, as at 26, whereas the opposite end passes through a bore 27 provided in the window frame near the top thereof. The free end of the cord at the rear of the window frame may carry a ring 28, a knot, or other suitable means whereby the cord may be secured at different elevations along the rear of the window frame. For example, the ring 28 may be slipped onto any one of a series of pins or headed studs 29 projecting from the rear of the frame, thereby to hold the movable shade member at one of a number of elevations beneath the canopy. In the drawing, the movable shade member is shown at the lowest possible elevation for maximum protection against the elements of nature. When the shade member is elevated to the inoperative position, within the canopy, the ring 28 will engage the lowermost anchorage member or stud 29.

In accordance with common practice in the awning field, the cord 25 may be divided at some point intermediate its ends, in order that equalized lifting force may be applied to opposite sides of the movable shade member, in the interest of smooth operation. As an alternative, two reaches of cord may be utilized, having a common terminus at the ring 28. This practice is so common in the art as to require no detailed explanation.

Suitable pulleys or other means to reduce wear upon the cord or cords, may be provided wherever the cords are subject to sharp bending strains during manipulation of the shade member 10. Most awnings are thusly equipped in accordance with everyday practice, as will be readily understood.

Referring to the Fig. 3 modification, there is shown a simplified and inexpensive canopy 33 devoid of side panels, into which may project the movable shade member 10, in precisely the manner previously described in the explanation of Figs. 1 and 2. The canopy 33 may be simply formed from a single rectangular sheet of metal, by bending same along its opposite margins to provide the securing flange 34 and the drop or skirt 14. The drop or skirt in this case may be omitted, if desired. Flange 34 may be pierced at

intervals along its length, to accommodate lag screws or other fasteners 35.

Attention is now directed to the modified structure illustrated by Figs. 4 and 5. This structure is more elaborate than those previously described, and has a number of very desirable features which render it superior as to performance, operability, and appearance. As before, the window frame parts are designated 6, 7 and 8, and the entire awning structure is supported thereby. The awning structure in this instance comprises an upper fixed canopy 40, and a plurality of movable shade members 41 and 42. The lowermost shade member is dimensioned to fit within the shade member above it when partly elevated, and further elevating of the shade members disposes both within the upper fixed canopy. The elevating and lowering movements of the shade members are controlled by a cord or cable 43 attached at 44 to a structural member or bar 45 of the lower shade member, and this control or actuating means may be operated in the manner heretofore explained in describing Figs. 1 to 3, from a location inside the building, if desired.

The fixed canopy 40 may be formed from a single sheet of material, such as aluminum or other metal, properly punched and formed to provide a front panel 46, opposed triangular side panels 47, and an inwardly turned integral flange 48 on each side panel to overlie the window frame stile 6. By means of screws or other fasteners 49, the flanges may be fixed to the stile. A horizontal flange 50 integral with the front panel 46, may be fastened as at 51 to the head 7 of the window frame to further support the canopy. The decorative skirt such as 14 of Fig. 1, has been omitted from Fig. 5 to simplify the drawing, but such skirts or their equivalent may be applied to the canopy, and also to the movable shade members, if desired.

The shade members are adapted for sliding movement vertically upon a pair of upright guide members 52, secured one to each stile of the window frame. Only one such guide member is shown upon Fig. 5, but the other is identical and fixed to the remaining stile at the right side of the window. A screw or other fastener 53 secures the upper end of the guide member to the stile, whereas a lag bolt 54 or the like secures the lower end thereof. The head of the lag bolt may serve as a stop for downward movement of the shade members, as will presently appear. The guide member 52 may overlie the flange 48, if the flange is made wide as shown. It should be understood that both guide members rest substantially flat against the frame stiles.

Each guide member is of C-shape, or the equivalent thereof, with a back 55 and a pair of in-turned opposed flanges 56 and 57 spaced from the back and from one another. The guide members are of a length approximating the total height of the awning elements 40, 41 and 42, when dropped to the operative position. The length is shown slightly exaggerated in Fig. 5, due to the effort to clearly disclose the structure; but in practice, the shades 41 and 42 will not lower quite as far as shown. In other words, the upper edge of shade 41 should rest at the lower edge of the canopy, and the upper edge of shade 42 should rest at the level of the lower edge of shade 41, when the shades are lowered to the maximum extent, as in Fig. 4.

The intermediate shade 41, like the canopy 40, has a front panel, opposed triangular side panels, and an inturned flange 58 on each side panel.

The length of shade member 41 between its opposed side panels, is slightly less than the length of the canopy so that shade member 41 may be elevated into the open bottom of the canopy, guided by the guide members 52. For this purpose, the flanges 58 at opposite ends of the shade member 41 are each secured by means of welds or screws 59, to a slide 60 that travels along one flange of the guide member 52. The slide may be of the same cross-sectional shape as the guide member, having a flange 61 hooking into the flange 56 of the guide member and slidably thereon. The length of slide 60 approximates the height of the shade members 41 and 42, so that when the intermediate shade member is lowered to the position of Fig. 4, the lower end 62 of its slide is stepped by the head of the screw 54 to establish the elevation of the shade member 41. The right-hand end of the shade member is similarly guided and supported.

The lowermost shade member 42 may be constructed like the shade member above it, if desired; however, as herein disclosed the lower shade member is made up in sections and parts including a translucent plastic panel 63 which excludes rain and wind, while at the same time permitting some light to pass. The panel 63 may be colored, and may incorporate a degree of opacity to reduce light passage to some extent. If desired, the plastic front panel 63 may be flat rather than corrugated as shown.

Shade member 42 may consist of a pair of triangular side frames 64 connected together at corresponding corners by the bar or brace 45. The bar may have its opposite ends each secured to a side frame 64 by means of welds, rivets, or screws 65 passing through a flange 66 integral with the frame. The flange in turn is secured to a slide 67 by means of suitable fasteners 68, so that vertical sliding movement of the slide is accompanied by corresponding movement of the lower shade member. As will be understood, the plastic panel 63 may be secured to the frame 64 and its companion frame at the right end of the shade member, by means of fasteners inserted through the perforations 69 and 70. Similarly, the lower edge of the panel may be secured to the skirt piece 71 which spans the forward corners 72 of the two side frames.

Part 71 is preferably formed of a single piece of metal bent to provide the panel support flange 73, a skirt 74, and an inwardly directed ledge 75. Ledge 75 may overlie a similar ledge 76 formed as an integral part of frame 64, and the two ledges then are joined at the overlap in any suitable manner to provide a rigid structure carrying the plastic panel. The dependency indicated at 77 is an integral skirt similar to skirt 74. It should be understood that the structural arrangement shown at the left of Fig. 5 will be duplicated at the right end of the awning structure.

Attention is directed to the fact that the slide 67 is of substantial C-shape, like the parts 52 and 60, but its length is reduced to approximately half the length of slide 60. This permits the short slide 67 to travel along the flange 57 of the guide member 52, to the top portion of the latter when the cord 43 is raised. Moreover, the slide 67 moves along the guide member relative to the other slide 60, as the lower shade member 42 is pulled upwardly into the adjacent shade member 41. The horizontal length of the lower shade member is made slightly less than that of the shade member 41, to ensure the aforesaid nesting of the shade members. When the lower shade

member is elevated sufficiently to bring it in contact with the shade member next above, both shade members proceed to enter the canopy 40 upon continued raising of the cord 43. The slides 60 and 67 thereupon are caused to travel in unison along the flanges 56 and 57 of the guide member 52, until they both reach a point near the upper end of the guide member.

When the cord is released to dispose the shade members to the operative or lowered position, both shade members travel downwardly in the nested relationship until the lower end of slide 60 strikes the abutment 54, thereby fixing the elevation of shade member 41. The lower shade member continues to descend until the lower end 79 of its slide 67 strikes the same abutment 54, at which time the shade members will be found to bear the relationship illustrated upon Fig. 4.

An awning constructed as above described is highly effective in operation, as well as pleasing of appearance. It is mechanically superior to any known all-metal awning available on the market, and the plastic panel feature is of particular advantage in its function of deflecting rain and wind, without undue darkening of the room with which the awning is associated. It is possible, of course, to construct the canopies as well as the adjustable shade members, from translucent sheet material; however, in the preferred form of the invention only the lowermost shade member is translucent, and the remaining elements are of sheet metal.

As previously stated herein, the canopies and shade members may be fabricated from hard sheet material of any suitable type or gauge, possessing the required rigidity and durability. It is at once evident that each of these parts may be punched and formed from a single sheet, if desired, to avoid the use of joints that require connection as a separate manufacturing operation. Advantageous also to the production method, is the fact that the canopies and the shade members may be made similar in size and shape, except for a slight reduction in the length of the movable shade members to permit nesting. To enhance the appearance, the canopies and shade members may be painted with alternately colored stripes to simulate awning fabric, or other forms of decoration may be applied.

With excellent results, awning structures of the character disclosed herein have been formed of sheet plastic, sheet iron, and sheet aluminum, both plain and corrugated. Hammered aluminum sheet has also been used with pleasing effects resulting.

As was pointed out in the explanation of Figs. 1 to 3, the cord or actuating means 43 of Fig. 5 may be divided so as to elevate the lowermost shade member from its opposite ends, rather than from the middle point 44. That is to say, the ends of a divided cord may exert lifting force at the slides 67 at opposite ends of the lower shade member, to ensure smooth operation, as is usual in the awning art.

It is to be understood that various modifications and changes in the structural details of the device may be made, within the scope of the appended claims, without departing from the spirit of the invention.

What I claim is:

1. An awning structure which comprises in combination, a canopy having a forwardly and downwardly inclined panel providing an open bottom for the canopy, integral horizontal and vertical rigid flanges on the canopy for rigidly

mounting the latter upon the header and the stiles, respectively, of a window frame, a pair of upright guides fixed relative to the frame at opposite sides thereof, said guides each including a pair of longitudinal spaced flanges, a movable shade member including a forwardly and downwardly inclined panel sloping in substantially the same direction as the canopy panel, means on the shade member slidably engaging one flange of each guide, for sliding vertical movement thereon, to guide the shade member bodily into the open bottom of the canopy when elevated, a second movable shade member including flanges of the guides, to guide said second shade member vertically toward and from the first mentioned shade member, and means for controlling the elevations of the shade members relative to the canopy.

2. An awning structure which comprises in combination, a canopy having a forwardly and downwardly inclined panel providing an open bottom for the canopy, means for fixing the canopy to the top portion of a window frame, a pair of upright guides fixed to the frame at opposite sides thereof, said guides being each of channel formation to include a back abutting the window frame, and a pair of inturned opposed flanges spaced from the back and from one another, a shiftable intermediate shade approximating the shape of the canopy but reduced in size sufficiently for nesting into the open bottom of the canopy, a slide at each end of the shade, said slides each consisting of a strip member having a back secured to the shade, and an inturned flange hooked in sliding engagement with one inturned flange of one of the upright guides aforesaid, a lower shade shiftable upwardly into the intermediate shade, a slide at each end of the lower shade, each consisting of a strip member having a back secured to the lower shade, and an inturned flange slidably hooked in engagement with the remaining inturned flange of each upright guide, and means for elevating and lowering the shades relative to the canopy.

3. An awning structure which comprises in combination, a canopy having a forwardly and downwardly inclined panel providing an open bottom for the canopy, means for fixing the canopy to the top portion of a window frame, a pair of upright guides fixed to the frame at opposite sides thereof, said guides being each of C formation to include a back abutting the window frame, and a pair of inturned opposed flanges spaced from the back and from one another, a lower shade and an intermediate shade shiftable along the upright guides, the intermediate shade approximating the shape of the canopy but reduced in size sufficiently for nesting into the open bottom of the canopy, and the lower shade being likewise shaped and reduced in size to nest within the intermediate shade, a pair of slides on each shade near the opposite ends thereof, said slides each consisting of a vertical strip member having a hook-shaped flange formed along the length thereof, the hook-shaped flanges of the strip members on the lower shade being slidably engaged with innermost flanges of the frame-supported upright guides, and the hook-shaped flanges of the strip members on the intermediate shade being slidably engaged with the outermost flanges of said upright guides, and means for elevating and lowering the shades relative to the canopy.

4. An awning structure which comprises in combination, a canopy having a forwardly and downwardly inclined panel providing an open bottom for the canopy, means for fixing the canopy to the top portion of a window frame, a pair of upright guides fixed to the frame at opposite sides thereof, said guides being each of C formation to include a back abutting the window frame, and a pair of inturned opposed flanges spaced from the back and from one another, a lower shade and an intermediate shade shiftable along the upright guides, the intermediate shade approximating the shape of the canopy but reduced in size sufficiently for nesting into the open bottom of the canopy, and the lower shade being likewise shaped and reduced in size to nest within the intermediate shade, a pair of slides on each shade near the opposite ends thereof, said slides each consisting of a vertical strip member having a hook-shaped flange formed along the length thereof, the hook-shaped flanges of the strip members on the lower shade being slidably engaged with innermost flanges of the frame-supported upright guides, and the hook-shaped flanges of the strip members on the intermediate shade being slidably engaged with the outermost flanges of said upright guides, the length of the slides on the intermediate shade being about twice as long as the slides on the lower shade and depending to a position behind the lower shade, a stop on each upright guide establishing the lower limit of shifting movement of the slides of both shades, and means for elevating and lowering the shades relative to the canopy.

5. An awning structure which comprises in combination, a canopy having a forwardly and downwardly inclined panel providing an open bottom for the canopy, means for fixing the canopy to the top portion of a window frame, a pair of upright guides fixed to the frame at opposite sides thereof, said guides being each of channel formation to include a back abutting the window frame, and a pair of inturned opposed flanges spaced from the back and from one another, a shiftable intermediate shade approximating the shape of the canopy but reduced in size sufficiently for nesting into the open bottom of the canopy, a slide at each end of the shade including an inturned flange hooked in sliding engagement with one inturned flange of one of the upright guides aforesaid, a lower shade shiftable upwardly into the intermediate shade, a slide at each end of the lower shade including an inturned flange slidably hooked in engagement with the remaining opposed inturned flange of each upright guide, and means for elevating and lowering the shades relative to the canopy.

JAMES N. DUGAN.
